US0D1053532S

(12) **United States Design Patent** (10) Patent No.: **US D1,053,532 S**
(45) Date of Patent: ** Dec. 10, 2024

(54) **SHOE**
(71) Applicant: **adidas AG**, Herzogenaurach (DE)
(72) Inventor: **James Thompson**, Herzogenaurach (DE)
(73) Assignee: **adidas AG**, Herzogenaurach (DE)
(**) Term: **15 Years**
(21) Appl. No.: **29/892,493**
(22) Filed: **May 18, 2023**

Related U.S. Application Data
(63) Continuation of application No. 29/852,850, filed on Sep. 9, 2022, now Pat. No. Des. 990,846, which is a continuation of application No. 29/777,634, filed on Apr. 7, 2021, now Pat. No. Des. 966,669, which is a continuation of application No. 29/719,889, filed on Jan. 8, 2020, now Pat. No. Des. 915,749, which is a continuation of application No. 29/694,634, filed on Jun. 12, 2019, now Pat. No. Des. 875,359, which is a continuation of application No. 29/614,545, filed on Aug. 21, 2017, now Pat. No. Des. 851,889.

CLAIM

The ornamental design for a shoe, as shown and described.

DESCRIPTION

FIG. 1 is a front medial perspective view of an embodiment of a shoe.

FIG. 2 is a medial side view of the shoe of FIG. 1; and, FIG. 3 is a rear view of the shoe of FIG. 1.

The broken lines and the reduced opacity areas within the broken lines show portions of the shoe which form no part of the claimed design.

1 Claim, 3 Drawing Sheets

FIG. 1

FIG. 2

FIG. 3
